UNITED STATES PATENT OFFICE.

GEORGE O. DRAPER, OF HOPEDALE, MASSACHUSETTS, ASSIGNOR TO THE DRAPER COMPANY, OF SAME PLACE AND PORTLAND, MAINE.

RING-SPINNING MACHINE.

SPECIFICATION forming part of Letters Patent No. 622,181, dated March 28, 1899.

Application filed June 4, 1898. Serial No. 682,539. (No model.)

To all whom it may concern:

Be it known that I, GEORGE O. DRAPER, of Hopedale, county of Worcester, State of Massachusetts, have invented an Improvement in 5 Ring-Spinning Machines, of which the following description, in connection with the accompanying drawings, is a specification, like letters and figures on the drawings representing like parts.

10 This invention relates to ring-spinning machines wherein the usual separators are displaced by a guard or curtain longitudinally extended back of the spindles to receive the impact of the yarn and prevent excessive ballooning, such a device being shown in United 15 States Patent No. 599,539, dated February 22, 1898.

In another application, filed on the 4th day of June, 1898, Serial No. 682,538, I have shown 20 a flexible curtain suspended from its upper edge back of the spindles, the supports for the guard or curtain being entirely independent of the ring-rail.

My present invention has for its object the 25 production of apparatus of the same general type embodying several novel features; but herein I employ a substantially inflexible guard supported in such manner as to traverse in unison with the ring-rail. Preferably 30 the guard is mounted upon the ring-rail, and in order to obviate any interference with the guide or thread board at the upper end of the traverse I have provided means for stopping the upward movement of the guard, the supports therefor being arranged to yield for the 35 purpose.

Figure 1 is a transverse sectional view of a sufficient portion of a ring-spinning machine to be understood, with the preferred embodiment of my invention applied thereto, the 40 ring-rail being shown in full and dotted lines at the bottom and top of its traverse, respectively; and Fig. 2 is a perspective detail, enlarged, to be described.

45 The frame A, roller-beam A', spindle and ring-rails B and R, respectively, the spindles S, and the thread or guide board T may be and are of usual or well-known construction, the ring-rail being provided with rings R^X, 50 the yarn y leading downward from the usual pigtails t^X.

I prefer to make the guard G of thin sheet metal or other suitable light material substantially inflexible and which will retain its shape, the preferred form being herein shown 55 as curved or rounded transversely or from top to bottom, with its convex surface outward toward the spindles. I have herein shown the guard as supported by the ring-rail itself, though it might be otherwise 60 mounted—as, for instance, on the traverse-rodso—so long as the guard traverses with the ring-rail. Brackets a are attached to the front of the ring-rail, preferably one at each end thereof, to which are pivoted at a' upwardly 65 and rearwardly extended arms a², the free ends of the arms passing through slots g in the guard and extending beyond the latter, as at a³.

Brackets b, having ears b', are secured to 70 the rear face of the guard, and the arms a² are pivotally connected with said ears at b^X, a shoulder a⁴ on the arm normally resting against a stop b² on the bracket b. (See Fig. 2.)

I prefer to weight the lower edge of the 75 guard, as by attaching a rod g^X thereto, so that the shoulder and stop referred to will be normally held in engagement, with the guard in proper upright position.

A suitable spring s (see dotted lines, Fig. 1) 80 is provided at the fulcrum a' of each arm a², one end of said spring being attached to the arm and the other end to the bracket a, the winding of the spring being such that the arms are normally held lifted in full-line position, Fig. 1, with a shoulder a⁵ abutting against the top of the bracket a. As the ring-rail approaches the upper end of its traverse the guard would, unless prevented, interfere 85 with the thread-board T, and I prevent such interference by mounting, preferably, a roll c on a stand c^X, attached to a part of the frame, as the roller-beam A', said roll being in the path of the extension a³ of the supporting-arm a². When said extension 90 engages the roll, the upward movement of the guard is stopped, the arms a² then rocking on their fulcrum a', as shown in dotted lines Fig. 1. The guard G then rocks by gravity 95 on its pivots b^X relatively to the arms and is thus prevented from interfering with the ring-rail as the latter completes its traverse 100.

into dotted-line position, Fig. 1. The rolls *c* travel along the extensions *a*³ and reduce the friction thereupon during movement of the arms *a*² relative to the ring-rail. When the 5 ring-rail is near the upper end of its traverse, there is practically no necessity for the guard, so that the stoppage of the latter, as described, is unobjectionable.

By weighting the lower edge of the guard 10 it is maintained by gravity in operative position.

The supporting-arms may be depressed by hand when doffing, if necessary, to thus keep the guard out of the way at such time.

15 Any suitable lock or catch can be provided to retain the arms so depressed, the lock or catch being liberated by the operator when starting the frame after doffing.

I have shown in Fig. 1 a very simple form 20 of lock—viz., a spring bolt or dog 75, mounted in a housing on a bracket 80, attached to the main frame, a portion of the extension *a*³ of one of the supporting-arms being shown in Fig. 1 in dotted lines as engaged by the 25 bolt.

Having fully described my invention, what I claim, and desire to secure by Letters Patent, is—

1. In a ring-spinning machine, the reciprocating ring-rail, a guard, which in vertical section is curved from top to bottom, extended 30 behind the spindles with its convex surface toward the spindles, and means to support the guard and traverse it in unison with the 35 ring-rail.

2. In a ring-spinning machine, the reciprocating ring-rail, a substantially inflexible guard back of the spindles and yieldingly mounted to traverse with the ring-rail, and 40 means to stop the movement of the guard during the upper part of the traverse of the ring-rail.

3. In a ring-spinning machine, the reciprocating ring-rail, yieldingly-mounted supports 45 on the ring-rail, a substantially inflexible guard back of the spindles and pivotally connected with said supports and maintained by

gravity in upright position, and means to stop the movement of the free ends of said supports at the upper end of the traverse. 50

4. In a ring-spinning machine, a guard extended longitudinally back of the spindles, the ring-rail, spring-controlled supports mounted thereon and connected with the guard, stops to normally maintain the supports in elevated position, and means to stop the upward movement of the guard at the upper portion of the traverse. 55

5. In a ring-spinning machine, a guard extended longitudinally behind the spindles, supports therefor, adapted to traverse in unison with the ring-rail, and means to stop the upward movement of the guard during the completion of the traverse at the upper end thereof. 60

6. In a ring-spinning machine, a substantially inflexible guard extended longitudinally behind the spindles, the ring-rail, rocking arms mounted thereon and pivotally connected with the guard, the free ends of the 70 arms projecting beyond the guard, and fixed stops to engage said projecting ends as the ring-rail rises, to thereby check the upward movement of the guard. 75

7. In a ring-spinning machine, a guard curved from top to bottom in vertical section and pivotally mounted on substantially horizontal pivots, and extended longitudinally back of the spindles with its convex surface turned toward them, said pivots being located 80 below the top of the guard. 80

8. In a ring-spinning machine, a guard extended longitudinally back of the spindles and substantially horizontal pivots therefor between its upper and lower edges, the weight 85 of the guard being distributed to present a heavier section below the pivot thereof.

In testimony whereof I have signed my name to this specification in the presence of two subscribing witnesses.

GEORGE O. DRAPER.
